UNITED STATES PATENT OFFICE.

ROLLIN L. DRAKE, OF PORT ARTHUR, TEXAS, ASSIGNOR TO THE TEXAS COMPANY, OF NEW YORK, N. Y., A CORPORATION OF TEXAS.

CAN.

Application filed January 15, 1924. Serial No. 686,278.

This invention relates to cans and more particularly to oil cans which can conveniently be carried in automobiles.

One of the objects of the invention is to provide a compact can which can be conveniently packed, together with other cans, without damaging its spout.

Another object of the invention is to provide a can which can be conveniently and easily handled.

Another object is to provide a can that may be lifted by the spout acting as a handle, making no other handle necessary.

Another object is to provide a can which may be sealed against unauthorized tampering after it has been filled.

The invention has particular reference to certain novel features of construction and arrangement of parts, an example of which 20 is given in the accompanying drawings in which:

Fig. 1 is a view in side elevation of a can embodying the present invention.

Fig. 2 is a plan view of the same can.

Fig. 3 is an enlarged sectional view of the can dome and spout in non-operative position.

Fig. 4 is a view taken on the line 4—4 of Fig. 3, and

Fig. 5 is an enlarged sectional view of the can dome and a portion of the spout in operative position.

Referring to the drawings the invention comprises a can 10, preferably made of a light yet durable metal, such, for example, as tin, having a substantially rectangular base and top, the top 12 being provided with openings 13 and 14. The opening 14 is normally closed by a threaded neck 15 upon which a cap 16 is screwed. To prevent tampering with the contents of the can a metal disk (not shown) crimped to the base of threaded neck 15 which is soldered over opening 14 after the can has been filled. The disk may be punctured to admit air when desired to dispense the contents of the can through the other opening 13 and spout 22.

The opening 13 is controlled by an outlet structure which comprises a fixed portion in the form of a neck or upwardly projecting peripheral flange 20 which is soldered or otherwise secured to the top 12, and a movable portion adapted to rotate within the neck 20. The movable portion comprises a

dome 21 and a tapered pouring spout 22 in open communication with the dome. The wall of the dome 21 adjacent its lower or open end is flared outwardly to provide a peripheral flange 30.

Midway between the upper and lower extremities of the interior of the neck 20, a circular disk 23 having an opening or port 24 therein is secured. A circular gasket 25 is positioned within the neck 20 so that it rests upon the disk 23. The gasket is provided with an opening or port of substantially the same shape as that of the opening 24. Directly above and resting upon the gasket 25 is a second circular disk 27, likewise provided with an opening or port 28 corresponding in shape and size to the opening 24. The disk 27 is provided around the opening 28 with a downwardly projecting peripheral flange 29 which is adapted to project through and engage the walls around the opening in the gasket 25 so that any rotary motion of the disk is imparted directly to the gasket in order that the two members may move together. The upper 70 surface of the disk 27 is soldered or otherwise secured to the lower face of the flange 30 of the dome 21 thus forming a substantially chambered member with the disk 27 as its base. The upper extremity of the neck 20 is crimped inwardly as at 31 so that the crimped portion serves to maintain the disk 27 and the gasket 25 in position within the neck 20.

The openings 24 and 28 are so positioned 90 that they can be made to register with one another by simply turning the dome 21. It is understood that the disk 23 is secured in a fixed position and that the gasket 25 and the disk 27 are rotated as a unit until the openings therein register with the opening 24 in the disk 23. Figure 3 shows the position of the movable members when the openings are not in registry, while Figure 5 shows the openings registering with one another so that the contents of the can may be poured therefrom through the dome 21 and the spout 22.

When the openings in the movable members are out of registry with the opening 24 in the fixed member, communication between the pouring spout and the can is cut off and the pouring spout is in the position shown in Figures 1 and 2; that is, the spout does not project beyond the sides of the can. In this position the spout serves as a con-

venient handle by means of which the can may easily be carried. Furthermore, when a number of cans are packed for shipment the likelihood of damage to the spout is minimized in view of the fact that it is confined entirely within the limits of the top of the can.

The side walls 35 and 36 of the can are each provided with an elongated finger recess 37 by means of which the can may be easily gripped while the contents are being poured therefrom.

A frangible metal strip 40 is secured at one of its ends to the neck 20 and at its other end to the dome 21. As long as the strip remains unbroken the dome 21 cannot be turned to bring the openings in the movable members into registry with the opening 24. Upon receipt of the can it is simply necessary for the consumer to break the thin metal strip or seal after which the dome can be turned at will. This strip when affixed at the time the can is filled assures the

consumer that none of the contents of the can have been poured off prior to the receipt of the same by him.

A can of preferred form and construction has been illustrated and described for the purpose of showing a way in which this invention may be practiced, but the inventive thought upon which this application is based is broader than this illustrative embodiment thereof. It is, therefore, understood that the scope of the invention is not limited by the present disclosure, reference being had to the appended claim for that purpose.

What I claim is:

A rectangular shaped can formed with opposed recesses in its opposite sides near one end of the can, and a dispensing spout disposed in the top of the can near the opposite end thereof.

In witness whereof I have hereunto set my hand this 4th day of January, 1923.

ROLLIN L. DRAKE.
